UNITED STATES PATENT OFFICE.

LESTER HAFT, OF NEW YORK, N. Y.

LIGHTING SET.

Application filed March 11, 1921. Serial No. 451,635.

To all whom it may concern:

Be it known that I, LESTER HAFT, a citizen of the United States, and a resident of the city, county, and State of New York, have invented certain new and useful Improvements in Lighting Sets, of which the following is a specification.

My invention relates to the illumination of objects, such for example as Christmas trees, and, more particularly, to an electric illuminating set of the type which has become known to the trade as a Christmas tree, or decorative, outfit.

Such outfits, as they have long since become standardized, consist either of a single set of eight miniature lamps connected together in series, about a foot apart, and with lead wires of convenient length connected to the terminals of an ordinary screw attachment plug, for connection to the usual lamp socket in a lighting circuit, or of sixteen, twenty-four, or thirty-two such lamps connected together eight in a series and with the lead wires of each series tapped into a junction box the leads of which are in turn connected with an attachment plug. The usual 110 to 120 volt potential on the lighting circuit is thus subdivided by eight, so that each miniature lamp in an outfit receives approximately fifteen volts and is of such reduced brilliancy as to simulate a candle.

Heretofore, therefore, it has been necessary, in order to suitably illuminate large objects or trees, or when greater brilliancy of illumination was desired, to purchase a number of these small outfits or one or more of the larger outfits as required and to find a separate lamp socket, or other source of current, to which to attach each separate outfit employed. Dealers have accordingly been obliged to buy, and to carry in stock, such an arbitrarily selected assortment of the four different sizes of outfits as each might think necessary for his trade.

The object of the present invention is to obviate the above, and other, defects in the prevailing standard practice, by providing an improved or unitary outfit, of simple construction and of low cost, which can either be used alone or can be readily connected one to another in an indefinite series, without the use of tools and with no more skill than that possessed by the average adult or child, and which thus serves as a unit for a flexible system capable of expansion and contraction as required.

To this end, I make use of an outfit with a single series of eight lamps and I incorporate therein, and preferably as a permanent part thereof, an ordinary threaded socket or other standard electric coupling member, of standard lamp size adapted to receive the attachment plug of a second outfit, which coupling member is connected in multiple with the lead wires of the outfit so that a second, and each additional, outfit connected on thereto will receive across its terminals the full voltage of the lighting circuit to which the outfit is attached.

As a secondary feature I provide each outfit with a screw cap or plug of insulating material which is inserted in the socket and is intended to remain therein until its removal is required for the attachment to the socket of a second outfit, thus safeguarding against accidental shock or short-circuit when the outfit is in use.

The invention will be clearly understood by reference to the accompanying drawings wherein—

Figure 1 is a view, largely diagrammatic, of one form of my improved lighting set or unit; Fig. 2 is a similar view of a slightly modified form thereof; and Fig. 3 is a detached side view of the screw cap usually provided with each outfit.

As here illustrated the screw plug 10, an ordinary attachment plug adapted to be inserted in any standard socket in the usual lighting circuit, the two lead wires 11 attached to the terminals of the plug, and the miniature lamps 12 connected together in series constitute what has been referred to as the standard eight-lamp or single series lighting outfit, the lead wires thereof being covered in the usual manner either separately or in the form of a duplex cord or cable. Incorporated in and forming a part of this outfit is a threaded socket 13, adapted to receive the attachment plug 10, or a similar attachment plug of a second lighting outfit, the terminals of which are connected in multiple with the lead wires 11 by branch lead wires 11^a. The form shown in Fig. 2 differs from that illustrated in Fig. 1 only in the fact that the branch lead wires to the socket are attached to the main lead wires of the outfit within the attachment plug, or, what is the same thing, to the two terminals of the attachment plug, instead of at some point outside thereof. A screw cap or plug 14, of any suitable in-

sulating material or composition, is preferably provided with each outfit, being screwed into the socket 13 where it is expected to remain until its removal is required for the attachment to the socket of the plug of a second outfit, thus protecting the metallic parts of the socket from injury during handling and safeguarding against accidents from shock or short-circuit when the outfit is in use.

Among the new and beneficial results produced by my improved or unitary lighting set may be mentioned the following: In the first place, production and marketing are simplified and cheapened, since, the sets being all of a single size and standard, the old junction box is eliminated and it is no longer necessary to make sets of different sizes and to provide different sized boxes for different sized sets. Again, jobbers and retailers are relieved from the necessity of buying and carrying in stock, as formerly, a quantity of each of four different sized outfits, thus reducing the size of the stock which they are required to carry and rendering it all saleable. And, finally, it provides a flexible system of illumination, easily manipulated without tools and with only the skill possessed by the average child, which permits consumers to first purchase a small equipment at a minimum initial expenditure and then to add thereto from time to time by the purchase of more sets and, for any occasion, to connect up as many or few sets as required and to attach the entire series to a single lamp socket or other outlet from a lighting circuit, the eight lamps in each set uniformly receiving the entire voltage on the circuit, and which also facilitates the making of repairs, when a lamp breaks down in use, since for the purpose it is only necessary to disconnect the eight-lamp set in which the defective lamp is found instead of having to take down, as formerly, the entire outfit of say twenty-four or thirty-two lamps.

It will, of course, be understood that any of the ordinary forms of quick detachable connectors may be used in the place of and as an equivalent for the screw attachment plug, and that when such other form of connector is used the proper complementary connecting member is to be substituted for the threaded socket here shown and described by way of example.

What I claim as new, and desire to secure by Letters Patent, is—

1. A unitary Christmas tree lighting set comprising an attachment plug adapted to be inserted in a standard lamp socket, a plurality of miniature lamps connected together in series, lead wires connecting said lamps with the circuit terminals of the attachment plug, a complementary attachment member adapted to receive the similar attachment plug of a second lighting set, and lead wires connecting the terminals of said complementary attachment member in multiple with the lead wires of the lamps. 70

2. A unitary electric decorative lighting set comprising a quick detachable member of a standard electric circuit connecting couple, a plurality of miniature lamps connected together in series, lead wires connecting said lamps with the terminals of the coupling member, and a coupling member complementary to and having its terminals connected in multiple with the terminals of said first mentioned coupling member. 80

3. In a unitary decorative lighting set the combination, with the usual standard attachment plug, lead wires, and miniature lamps connected together in series, of a complementary attachment member connected in multiple with said lead wires and a cap of insulating material adapted to be inserted in said complementary attachment member to protect it from injury and as a safeguard against accidents from shock or short circuit. 85

In testimony whereof, I have affixed my signature to this specification.

LESTER HAFT.
